(57) **CLAIM**

The ornamental design for a carousel capsule holder, as shown and described.

DESCRIPTION

FIG. 1 is a perspective view of a carousel capsule holder showing the new design;

FIG. 2 is another perspective view of the carousel capsule holder of FIG. 1;

FIG. 3 is a front view of the carousel capsule holder of FIG. 1;

FIG. 4 is a top view of the carousel capsule holder of FIG. 1; and,

FIG. 5 is a bottom view of the carousel capsule holder of FIG. 1.

The difference in shading in the figures indicates a contrast of appearance and does not depict any particular color, texture, or material.

The broken lines in the drawings depict environmental subject matter only and form no part of the claimed design.

1 Claim, 4 Drawing Sheets
